PAUL ERNST PRESCHLIN, OF SCHLADERN-ON-THE-SIEG, GERMANY.

EQUALIZING DEVICE FOR PRINTING-MACHINES.

1,044,242.

Specification of Letters Patent.

Patented Nov. 12, 1912.

Application filed February 28, 1912. Serial No. 680,475.

To all whom it may concern:

Be it known that I, PAUL ERNST PRESCHLIN, a subject of the Emperor of Germany, and resident of Schladern-on-the-Sieg, Germany, have invented Improvements in Equalizing Devices for Printing-Machines, of which the following is a specification.

In the known printing-machines for printing long webs of fabric or paper, in which two or more printing rolls act on the same or adjoining places along the web, it is a necessity that all rolls, running at equal angular speed are given the same diameter, otherwise the smaller rolls would feed too slowly and if arranged behind the larger rolls, would hold back the web, which thereby is bound to tear. If however the smaller rolls are arranged in front of the larger rolls, the latter would feed too fast and thus cause continuous trouble and interruptions in the working of the machine. The differences in diameter of the printing rolls is a frequent occurrence caused by depriving them of their etching or engraving.

Now if one would venture to change the number of revolutions or the angular speed of the rolls, to agree with the different diameter of the printing rolls, in such way, that the feed of the web is carried out uniformly by all rolls, the impressions of the divers printing rolls on the common web would be displaced on every rotation for a certain distance and thus a faulty print would be obtained which is absolutely worthless. This drawback is particularly remarkable in printing with different colors, but also in printing illustrations in between text the displacements are very inconvenient. This drawback is done away with by the device forming the subject of the present invention, by which it is attained that two or more rotating rolls, which act on a common printing web or endless band and which make the same number of revolutions during a unit of time, may be given different diameters. Ways and means have been devised to compensate for the reduction in the diameter of the rolls deprived of their etching or engraving by giving the rolls their original diameter. However this is a task

which is expensive. In making use of the present invention it is not necessary to bring the rolls back to their original diameter every time they are prepared for a new etching or engraving, but only when the diameter is so much reduced that an equalization of the feed by the subject matter of the present invention is no longer possible.

According to the present invention a compensation is produced whereby the counter roll of one of the printing rolls is now and then lifted off from the latter, so as to release the web from the pressure and to allow a tension roller to act on the web intermediate of the two printing rolls so as to pull up the web to an amount corresponding to the difference in the diameter of the rolls, whereupon the said counter roll approaches its printing roll again and the tension roll returns to its original position.

In the accompanying drawing Figure 1 is a longitudinal section of a portion of a printing machine having the device embodying my invention attached thereto. Fig. 2 is a modification of a detail and Fig. 3 is a plan of a web or printed newspaper.

The web *a*, *b*, *c*, *d*, *e*, *f*, *g*, *h* (endless paper, fabric and the like) to be printed is taken from a reel *H* and led by aid of a number of guide rolls past the printing rolls *B* and *A*, which act together with the counter rolls *E* and *A¹* to print and feed the web. At both sides of the smaller printing roll *B* the web is led under movable tension rolls *C* and *C¹*, which are movable longitudinally to the machine simultaneously for instance by aid of a common slide or of levers *M* and *M¹*, which are connected by a link or rod *N*. A spring *K* tends to move the tension rollers from the position shown in dotted to that shown in full lines, in which they are arrested by a set-screw *D*.

The counter roll *E*, which may be coated with rubber or may be made to bear against an endless rubber band, is journaled on levers *O*, which are pivotally attached to a fixed part *P* of the machine-frame and said roll *E* is normally pressed by the roll *F*, which also counteracts its bending strains against the printing roll *B*, which is in posi-

tive driving connection with the printing roll A in such manner that both rotate at the same angular speed. The roll F, which is provided with a flattened or concave part G, is also driven in such way as to make a complete revolution on each revolution of the printing roll B. During the time, in which the counter roll E is rolling on the surface of the roll F, the printing is carried on by the roll A as well as by the roll B. At the same time the roll A feeds on the web to a greater extent than the smaller roll B, the tension roll C moving thereby from the position shown in full lines into that shown in dotted lines, thus allowing of a shortening of this part of the web. At the end of each revolution the concave part G of the roll F comes opposite the counter roll E, which for a moment extends into the cavity G by the action of the spring L, thus releasing the web from the pressure, exerted between the counter roll and the printing roll. This release has the effect of the tension rollers C and C¹ giving way to the tension of the spring K which return the tension rollers to their original position shown in full lines, and thus pull up so much of the web, as the roll A has fed more of the web than the roll B. This equalization takes place for instance, when newspapers or similar sheets are printed at such moment, when the margin not to be printed comes in between the counter roll and the printing roll, that is to say the places shown in Fig. 3 in hatched lines.

The lifting of the counter roll E can be carried out in different ways. In the modification shown in Fig. 2 the counter roll V of the printing roll T is journaled on arms Q¹ of bell crank levers Q, the other arm Q² of which being provided with an anti-friction roller U, bearing against the rim of a disk S provided with a cam R. On every revolution of the printing roll T and of the disk S connected with it, the cam R raises the roller U, thereby oscillating the bell crank lever Q thus increasing the tension of the spring W and thereby allowing the counter roll to release the web.

By adjusting the screw D, which can be done during the working of the machine, the amount of the intermittent motion of the tension rollers C and C¹ can be altered to exactly correspond with the difference of the diameters of the rolls A and B. The maximum of every equalization, should not be larger than the breadth of the zone to be left unprinted, as shown in Fig. 3. Evidently an equalizing device of the character described above can also be made use of when the printing roll A is of a less diameter than the printing roll B. In such case the counter roll A¹ would have to be raised instead of E, by correspondingly ar-

ranging the tension rollers. When however the counter roll of the roll B retains its lifting device, the tension rollers need only be movable in the other direction.

I claim:

1. In a printing machine having a plurality of printing rolls running at the same angular speed and having different diameters, a counter roll for each printing roll, one counter-roll adapted to be intermittently raised from its printing roll, a tension roll in front of the counter roll adapted to be raised and a second tension roll behind the counter roll, both tension rolls being adapted to move in unison and to bear on the web to be printed, so as to change the feed of the web, when released by the counter roll being raised from its printing roll.

2. In a machine for printing upon a web of paper, the combination of a pair of printing rolls of different diameters arranged one behind the other and rotatable at the same angular speed, a cylinder to press the web on one of said rolls and adapted to temporarily release its pressure on said web, a movable tension roll engaging the web between the two printing rolls adapted to be moved from its normal position by the tension on the web, caused by the unequal diameters of the printing rolls, and means to return the tension roll to its normal position automatically during said release of pressure.

3. In a machine for printing upon a web of paper, the combination of a pair of printing rolls of different diameters arranged one behind the other and rotatable at the same angular speed, a cylinder to press the web on one of said rolls means for temporarily liberating the web from the pressure of the printing roll and the pressure cylinder, a movable tension roll engaging the web between the printing rolls adapted to be moved from its normal position by the tension on the web, caused by the printing rolls of unequal diameter rotating at the same angular speed, and means to return the tension roll to its normal position automatically during the liberation of the web.

4. In a machine for printing upon a web of paper, the combination of a pair of printing rolls of different diameters arranged one behind the other and rotatable at the same angular speed, a cylinder to press the web on one of said rolls, means for temporarily liberating the web from the pressure of the printing roll and the pressure cylinder at regular intervals, a movable tension roll engaging the web between the printing rolls adapted to be moved from its normal position by the tension on the web, caused by the printing rolls of unequal diameter rotating at the same angular speed, and means to return the tension roll to its nor-

mal position automatically during the lib-
eration of the web.

5. In a machine for printing upon a paper
web, the combination of a pair of printing
rolls of different diameters and rotatable at
the same angular speed, and means adapted
to equalize the difference in the feed of the

web due to said unequal diameters of the
printing rolls and the equal angular speed
of rotation thereof.
